UNITED STATES PATENT OFFICE.

SAMUEL DALE, OF BOONESBOROUGH, IOWA.

HOD-ELEVATOR.

SPECIFICATION forming part of Letters Patent No. 283,119, dated October 2, 1883.

Application filed August 21, 1883. (No model.)

To all whom it may concern:

Be it known that I, SAMUEL DALE, a citizen of the United States, and a resident of Boonesborough, in the county of Boone and State of Iowa, have invented certain new and useful Improvements in Hod-Elevators; and I do hereby declare that the following is a full, clear, and exact description of the invention, which will enable others skilled in the art to which it appertains to make and use the same, reference being had to the accompanying drawings, which form a part of this specification, and in which—

Figure 1 is a perspective view of my improved hod-elevator in operative position. Fig. 2 is an end view of the same, and Fig. 3 is a top view.

Similar letters of reference indicate corresponding parts in all the figures.

20 My invention has relation to hod-elevators; and it consists in the improved construction and combination of parts of the same, as will be hereinafter more fully described and claimed.

In the accompanying drawings, A represents 25 the lower story of a building which is in course of erection.

B indicate guide-posts, between which run the frames C C' which carry the hods.

D D' indicate arms which are secured upon 30 the top or floor of the story A, the meeting ends of the said arms being connected together by a cross-piece immediately above the opening through which the guide-posts B pass.

C C' represent the frames which carry the 35 hods, the upper edge of each frame being recessed for the reception of the hod, and having a supporting - piece, C'', secured upon its (frames C C') side, against which the handle of the hod rests. Upon either side of each frame

40 is fastened guiding-strips E, preferably of metal, which fit upon either side of the guide-posts, the frames C C' being further provided with a metal loop upon their tops, to which the hoisting-ropes are fastened.

45 Between the lower part of the arms D is journaled a hoisting drum or windlass, F, having secured upon its center a pulley-wheel, F', and upon either end a toothed wheel, G G', the teeth of the wheel G being inclined in an opposite direction to those of the wheel G', for the

purpose hereinafter specified. Upon either end of the windlass F is fastened a crank, H, by which the windlass may be rotated.

Between the upper part of the arms D is journaled an axle, I, having secured upon it, 55 near either end, between the arms D, a pulley-wheel, I', over which the hoisting-ropes J J' pass, one end of each of the said ropes being secured to the windlass F, one on either side of the pulley-wheel F'. A rope, K, passes 60 around the central pulley-wheel, F', and around a drum, L, supported in suitable bearings upon a spring-bar, L', the spring of the said bar serving to keep the rope K taut, thereby causing it to act to some extent as a brake to prevent the windlass F from turning too rapidly. 65

M M' represent pawls, which engage with the toothed wheels G G'.

N N represent supports pivoted at one end, 70 which may be pushed under the frames C C' when the latter are raised, in order to hold them in their elevated position.

By constructing my improved hod-elevator in the manner described it will be seen that it can be operated from either the upper platform or from the ground. In the latter case the operator makes use of the rope K to raise and lower the hods, the pawl M serving to hold the frame C' from slipping by means of the toothed wheel G, the pawl M' being raised to 80 allow the toothed wheel G', with which it is adapted to engage, to revolve freely beneath it while the said frame is being raised with a full hod upon it, the pawl M' performing the same office for the frame C, the pawl M being 85 then raised to allow the toothed wheel G' to revolve freely beneath it.

When it is desired to operate the apparatus from the upper platform, the cranks H can be utilized for that purpose, the pawls M and M' 90 being operated in the manner just described. The hoisting-ropes J J' are, as will be seen by reference to the drawings, wound around the windlass F in opposite directions, so that as one frame is being raised the other is lowered. 95

From the foregoing description, taken in connection with the accompanying drawings, the construction and manner of operating my improved hod-elevator will readily be understood without requiring further explanation. 100

It will be seen that my improved hod-elevator is simple in construction, and, being devoid of all complicated parts, is not liable to break or get out of order, while it can be constructed at a small cost. By its use all climbing of ladders is avoided, thereby effecting a great saving in time.

Having thus described my invention, I claim and desire to secure by Letters Patent of the United States—

1. The combination of the guide-posts B B, sliding frames C C', having guide-strips E, recesses O, and supporting-pieces C'', supporting-arms D D', windlass F, having central pulley-wheel, F', and toothed wheels G G', secured upon it at either end, with their teeth inclined in opposite directions, pawls M M', adapted to engage with the toothed wheels G G', axle I, having pulley-wheels I', hoisting-ropes J J', hoisting-drum L, hung in suitable bearings upon a spring-bar, L', and rope K, passing around the central pulley, F', and the drum L, as and for the purpose shown and set forth.

2. The combination of the guide-posts B B, sliding frames C C', having guide-strips E, recesses O, and supporting-pieces C'', supporting-arms D D', pivoted supports N N, windlass F, having central pulley-wheel, F', cranks H, and toothed wheels G G', secured upon it at either end, with their teeth inclined in opposite directions, pawls M M', adapted to engage with the toothed wheels G G', axle I, having pulley-wheels I', hoisting-ropes J J', hoisting-drum L, hung in suitable bearings upon a spring-bar, L', and rope K, passing around the central pulley, F', and the drum L, all constructed and arranged as and for the purpose shown and described.

In testimony that I claim the foregoing as my own I have hereunto affixed my signature in presence of two witnesses.

SAMUEL DALE.
